UNITED STATES PATENT OFFICE.

CESARE BARBIERI, OF NEW YORK, N. Y., ASSIGNOR TO THE VORTEX MFG. CO., A CORPORATION OF ILLINOIS.

MULTIPLE AUTOMATIC FOLDING MACHINE.

Application filed September 10, 1921. Serial No. 499,614.

To all whom it may concern:

Be it known that I, CESARE BARBIERI, a subject of the King of Italy, and a resident of the city of New York, in the county 5 of New York and State of New York, have invented certain new and useful Improvements in a Multiple Automatic Folding Machine; and I do hereby declare that the following is a full, clear, and exact description of the same, reference being had to the accompanying drawings, and to the numerals of reference marked thereon, which form a part of this specification.

This invention relates to an improved 15 multiple automatic folding machine especially adapted for manufacturing conical dishes of prepared paper ordinarily used for dispensing sundaes, ice cream or the like.

One of the important objects of this invention is the provision of a machine which will automatically form conical paper dishes from prepared blanks in large quantities automatically and by the simultaneous operation of a plurality of similar machines 25 all controlled by a master driving means.

Another important object of this invention is the provision of a machine adapted to automatically manufacture conical paper dishes from circular blanks of prepared 30 paper by folding sections of the same over each other and creasing these folded sections so that the dishes will permanently retain the conical shape given to them in the folding operation.

Still another important object of this invention is the provision of a multiple automatic dish forming machine wherein a series of like devices are driven in unison, each of the said devices being provided with 40 an adjusting means whereby it may be accurately timed to operate in unison with the other parts of the machine.

A further important object of this invention is the provision of a multiple automatic dish forming machine wherein each machine is provided with means for readily disengaging same from the common master driving device so that any number of the machines may be driven as desired.

Other and further important objects of 50 this invention will be apparent from the disclosures in the accompanying drawings and following specification.

The invention (in a preferred form) is il-

lustrated in the drawings and hereinafter 55 more fully described.

On the drawings; Figure 1 is a top plan view of one of the units of the improved multiple automatic dish forming machine with the master drive shown at the right 60 hand end thereof.

Figure 2 is a front elevation of the machine shown in Figure 1.

Figure 3 is an end view showing the single master drive for the plurality of the forming machines.

Figure 4 is a partial sectional view taken approximately on the line 4—4 of Figure 2 looking in the direction indicated by the arrows.

Figure 5 is a partial sectional view showing the blank feeding apparatus and is taken on the line 5—5 of Figure 1.

Figure 6 is a sectional view taken on the line 6—6 of Figure 5, parts being omitted.

Figure 7 is a sectional view showing the construction and operation of the folding mechanism.

Figure 8 is a side elevation of the folding means, showing the cams for operating.

Figure 9 is a sectional view taken approximately on the line 9—9 of Figure 7.

Figure 10 is a top plan view showing the dish forming means together with the means for removing the completed dishes.

Figure 11 is a side elevation of the apparatus shown in Figure 10.

Figure 12 is an enlarged plan view showing the circular blank after it has been inserted into the forming means.

Figure 13 is a sectional view showing one of the steps in the formation of the dish.

Figure 14 is a side view of Figure 13.

Figure 15 is a view similar to Figure 13 showing the completion of the dish forming 95 operation.

Figure 16 is an enlarged detail view showing a portion of the forming mechanism beneath the blank supporting table.

Figure 17 is a detail view of a portion of 100 the ejecting means for the completed dishes.

Figure 18 is a top plan view of the device shown in Figure 17.

Figure 19 is a diagrammatic view showing the relation of a plurality of the assembled 105 units.

As shown on the drawings, the reference numeral 20 indicates a pulley driven by

any convenient source of power by means of which the multiple machine is operated. In the apparatus shown the entire machine comprises ten separate units, but it is evident that the number may be varied as desired. The pulley 20 is mounted to rotate upon an axle or shaft 22 fixed upon a portion of the machine frame 24, (Figures 2 and 3). Mounted upon the shaft 22 and adapted to rotate with the pulley 20 is a pinion 26 in mesh with a gear wheel 28 which is in turn keyed upon a bearing sleeve 30. The gear 28 is an idler gear and mounted to rotate therewith is a pinion 32 likewise on the sleeve 30. The pinion 32 meshes with a gear 34 which drives the cam shaft 36 through a clutch member 37. Mounted to rotate on the shaft 36 is a sleeve 35 fixed to the cam shaft 36 so that the same may be rotated at will. A clutch member may be provided for each unit of the machine.

Keyed to the cam shaft 36 inside the frame 24 is an additional pinion 40 with a gear 41 on the shaft 42 meshing therewith. The gear 41 is keyed to the shaft 42 which extends through the frame in suitable bearings and has fixed to its outer end a disk 43 with a roller 44 (Figure 3) mounted on the periphery thereof which roller cooperates with a four-point Geneva gear 45. This Geneva gear 45 is mounted on and keyed to a rotatable shaft 46 which also drives a gear wheel 47 keyed thereon which in turn meshes with a driving pinion 48 mounted on a longitudinally extending driving shaft 49. The shafts for supporting the various driving gears and pinions are all mounted in suitable bearings in the machine frame. Mounted on the shaft 49 is a beveled gear 50 which drives a corresponding gear 51 connected in turn to the folding mechanism which forms the dishes.

Mounted on the cam shaft 36 is a beveled gear 52 which cooperates with a corresponding gear 53 mounted on a shaft 54 which drives the feeding means which delivers the blanks to the folding mechanism. As best shown in Figure 5, the shaft 54 extends to the forward part of the machine through a bearing sleeve 55 mounted on the front plate or bracket member 56 of the machine, and keyed upon the outer end of the shaft 54 is a pinion 58 in mesh with a gear wheel 59. The gear 59 in turn drives a smaller gear 60 mounted on a shaft 61 having adjustably mounted at its outer end a pair of mutilated gears 62 and 67 adapted to cooperate with two corresponding mutilated gears 64 and 63 respectively which drive the feeding rollers 66 and 65. An adjustable clutch member 68 is provided on the shaft 61 which is operated by a knurled knob 69 so that the relative position of the mutilated gears 62 and 67 with their re-

spective feed roller gears 64 and 63 may be adjusted as desired. The feed rollers 65 and 66 are provided with friction portions on their faces, preferably of rubber or the like as shown at 70 in Figure 6. These friction portions extend around only a portion of the periphery of the rollers so as to operate upon the paper blank to be fed only at predetermined times.

Mounted above the feed rollers 65 and 66 is a magazine 71 preferably circular in form provided for holding a plurality of the prepared disks 72 of which the dishes are formed, and keyed upon the shaft 54 adjacent the bevel gear 53 is a sprocket wheel 73 (Figures 2 and 5) having a chain 74 thereon which drives a corresponding sprocket wheel 75 keyed to a shaft 76 on the inner end of which is mounted a driving gear 77. The driving gear 77 is in mesh with a corresponding gear 78 which in turn drives a similar gear 79 connected to the auxiliary advancing rollers for the paper blank designated at 80 and 81 respectively (Figure 6). The upper roll 81 is movably mounted, being positioned in pivoted bearing members 82 which are held in downward position by means of coiled springs 83, as best shown in Figures 2, 5 and 6. A cam 85 is mounted upon the shaft 61 (see Figure 6), and adapted to cooperate with this cam is a lever 86 pivoted at 87 on a bracket and having a roller 88 upon the end thereof rolling on the face of the cam 85. The opposite end of the lever 86 is pivoted to a short link 89 connected in turn to a bell-crank lever 90 which is pivotally mounted on the frame of the machine by being keyed to a shaft 91. The upper end of the bell-crank lever 91 is formed in the shape of a finger 92 adapted to operate as a pusher member and a duplicate finger is provided on the other end of the shaft 91 to properly locate the disk of prepared paper in the forming mechanism after it has been fed forwardly by the feeding means just described. These pusher fingers 92 operate in unison (as shown in Figure 5) by the rotation of the shaft 91 which extends across the machine 115 in suitable brackets provided therefor, underneath the feed table 94, and the ends of the fingers 92 operate in suitable slots 93 provided therefor, in the feed table.

The shaft 49 is intermittently rotated by the action of the four-point Geneva gear 45 and the forming mechanism for the cups is driven thereby through the bevel gears 50 and 51. This forming mechanism is mounted on a shaft 95 (see Figure 4) provided with a clutch member 96 and an adjusting hand wheel 97 operates the clutch by means of which the forming elements may all be brought into proper timed relation with the feeding means on each individual ma- 130

chine. A locking pin or set screw 98 is provided in the clutch member 96 for retaining the adjusting wheel 97 and clutch in its desired position. The shaft 95 extends to the forward part of the machine through suitable bearings and at the outer end thereof is provided with a pivot pin 99 extending therethrough as best shown in Figure 7. Mounted on this pivot pin are the two gripper holding members 100 adapted to cooperate with each other and each having attached to its outer end a forwardly extending gripper plate 101. These gripper plates 101 are preferably in the form of flat triangular plates, as best shown in Figure 12, and are attached to the holding members 100 by suitable rivets or screws, as shown in Figure 7. The supporting members 100 and consequently the gripper plates 101 are normally held in closely contacting position by means of the helical spring 102 having its ends attached to pins 103 extending rearwardly from the gripper holding members 100. The gripper plates 101 are separated at predetermined times in order to permit of the insertion of a blank therebetween and adapted to cooperate therewith is a forming member 105 of a semi-conical shape, as best shown in Figures 4, 7, and 10. This forming member 105 is provided with two rearwardly extending arms 106 by means of which it is pivoted at 107 to the frame of the machine. A cross bar 108 connects the two arms 106 as best shown in Figure 10 and the rearward face of this bar is adapted to cooperate with the front circular face of the gripper supporting members 100 in such a manner that when the forming member 105 is lifted on its pivot 107 the forming members 101 are separated against the tension of the spring 102. This action is best shown in Figure 7. The means for lifting the forming member 105 is shown in Figure 8 and consists of a shoe 110 pivoted to an upstanding arm 111 of a form of bell-crank lever pivoted at 112 to the frame of the machine and having a roller 113 mounted thereon at its angle which cooperates with a suitable cam 114 on the cam shaft 36. This construction is also shown in Figure 9. As shown in Figure 16, the shoe 110 has a forwardly extending arm 115 pivoted at 116 to a suitable bracket on the frame and the arm 115 is formed with an extension 117 adapted to cooperate with the V-shaped slot in the table 94 which accommodates the triangular gripping plates 101 to properly form the paper dish and prevent any excess paper being pulled underneath the table in the rotation of the plates 101.

Mounted to extend through slots 119 in the table 94 is a pair of additional blank positioning members 118 adapted to slide in the slots. These positioning members

118 form the ends of upstanding arms 120, one of which is bent as shown at 121 in Figure 9 to join the other arm 120. The arm 120 is pivoted at 124 as shown in Figure 4 and is held in normal position by means of a coiled spring 125 and is operated by a roller 122 cooperating with a cam 123 mounted on the shaft 36. The positioning members 118 have a double function, namely, that of originally positioning the circular sheet of paper, and after the dish has been originally folded they are given an additional motion which results in a slight forward movement of the completed dish, after which the gripping members 101 are again brought together in order to additionally crease the paper to form a permanently shaped dish.

Positioned directly underneath a slot in the table 94 is a horizontally extending rod 127 (see Figures 1, 8 and 10) having slidably mounted thereon a bearing sleeve 128. This bearing sleeve is adapted to be reciprocated on the slide rod 127 by means of a link 129 pivoted thereto and operated by the upper arm of a bell-crank lever 130 pivoted at 131 on the machine frame and having its shorter arm cooperating with a cam operated lever 132 (see Figure 8) pivoted at 133 on the machine which has mounted at about its middle portion a cam roller 134 cooperating with a cam groove 135. Fixed to the bearing sleeve 128 is a forwardly extending arm 140 (see Figure 11) having at its end thereof a shoe member 141 attached thereto by means of a screw 142 and spring-held in operative position thereon. Extending rearwardly from the shoe member 141 is a spring or pressure member 144 (Figure 10) made in a curved shape to accommodate itself to the inside of a completed dish.

Pivoted at 150 on the frame of the machine (see Figure 8) is a rocking bar 151 having a cam roller 152 on the lower end thereof which rides on the outer surface of the cam wheel 135—114. The upper end of this rocking lever 151 is pivotally connected to a horizontally extending link 154 having its outer end eccentrically mounted upon a rotatable gear wheel 155, which gear wheel meshes with a corresponding gear or pinion 156, both mounted on suitable shafts at the outer end of the machine frame and immediately underneath the forward extension of the table 94. The shaft 157 upon which the gear wheel 156 is mounted extends underneath the table 94 as shown in Figures 1 and 11 and has keyed thereto a sleeve member 158 with one side made flat, and to this flat side are attached suitable spring pressure members 160 which extend through slots 161 provided therefor in the table. An additional stop member 166 is positioned upon the top of the table 94 as shown in Figure 12 to insure that the circular sheet

of prepared paper will be properly positioned by the cooperating fingers.

The operation is as follows: The machine having been set into operation by the revolution of the pulley 20, the clutch 37 is engaged which permits the driving of any number of the units of the multiple mechanism. The clutch being mounted on the cam shaft 36 revolves the same and with it the driving gears 40 and 41 which in turn impart motion to the disk 43 operating the four-point Geneva gear 45 by means of which the shaft 49 with its attached bevel gears 50 is intermittently rotated a quarter of a revolution at each turn of the disk 43. At the same time the cam shaft 36 by means of the beveled gear 52 and its coacting gear 53 drives the feeding mechanism which continuously delivers prepared disks of paper to the forming device. The delivery of the paper is accomplished by means of the feed rolls 65 and 66 having the rubber friction means thereon and actuated by the mutilated gears 67 and 62 cooperating with gears 63 and 64 which drive the feed rolls. It will be seen that if the feed roll 65 is rotated slightly in advance of the roll 66 the lowermost disk of paper 72 will be slightly buckled (as shown in Figure 6) on account of the faster or earlier movement of the friction member 70 on the roller 65, thereby separating the lowermost disk from the remaining disks in the magazine 71. The disk having been properly separated the rollers 65 and 66 are rotated in unison by means of their operating mutilated gears and feed the disk forward to the auxiliary feed rollers 81 and 80 which if desired may be slightly opened at this time by means of a cam action (not shown), the rollers 81 and 80 being normally held in coacting position by means of the coiled springs 83. These feed rollers are driven by means of the chain 74 on the sprocket wheels 73 and 75 cooperating with the gears 78, 79 and 77, and feed the disk forward over the smooth surface of the table 94. At the same time the cam 85 has acted to retract the pusher fingers 92 into their slots 93 in the table and after the paper has been pushed forward sufficiently by means of the auxiliary feed rollers 80 and 81 these pusher fingers 92 are actuated by means of the cam 85 to push the blank forward a slight additional distance into proper position on the table 94 and against the stop 166. At the same time the positioning fingers 118 are actuated in their slots 119 (as shown in Figure 12) to additionally position the disk of paper in the other direction, and to place it properly underneath the forming members 101 and 105. The gripper plates 101 are separated during the time the blank is being positioned, this separation being accomplished by means of the raising of the forming mem-

ber 105 about its pivot point 107 by means of the cam actuated lever 111 acting in conjunction with the shoe member 110 underneath the forming member 105. The cross bar 108 on the arms 106 of the forming member 105 cooperates with the forward face of the gripping holding members 100 to raise the same against the tension of the spring 102.

After the disk has been properly positioned the cam actuated shoe 110 is retracted allowing the forming member 105 to drop into proper position over the grippers 101, and these at the same time are brought together in gripping position by means of the spring 102. The action of the disk 43 and its attached roller 44 upon the Geneva gear 45 then commences and the gripping means are turned through a half revolution as shown in Figures 13, 14 and 15 to fold the paper into the form of a conical dish. After the gripping fingers have been turned through a complete half turn the cam again acts through the arm 111 and shoe 110 to separate the plates 101 and the pusher bars 118 are then given a very slight forward movement to push the completed cup out from the plates a short distance, after which the shoe 110 is again retracted allowing a further crease to be put into the formed dish 72 for the purpose of completing the permanent shaping of same. At this point the grippers are again separated and the ejecting arm 140 is moved forward by the sliding of the bearing sleeve 128 on the rod 127 which is accomplished through the levers 129 and 132. The ejecting member 140 contacts closely with the apex of the formed dish by means of the shoe 141 and pushes the same out over the smooth surface of the table 94 into ejecting position. At its outermost point the gripper members 160 operate through the slots 161 in the table to grip the folded over portion of the cup 72, this movement of the grippers 160 being caused by the lever 154 pivoted to the rocking arm 151.

Any or all of the units may be operated as desired and it will be seen that their action is entirely automatic, and the relation between the feeding and forming means may be very accurately timed.

I am aware that many changes may be made and numerous details of construction varied throughout a wide range without departing from the principles of this invention, and I therefore do not purpose limiting the patent granted otherwise than necessitated by the prior art.

I claim as my invention:

1. In an automatic machine for forming conical receptacles, the combination with an intermittently operated forming means, and gripping means adapted to co-act with said forming means to grip a prepared blank and turn a portion of the same through a part

- of a revolution to form a completed receptacle.
2. In an automatic machine for forming conical receptacles, the combination with a forming means, gripping means adapted to co-act with said forming means to grip a prepared blank and turn a portion of the same through a part of a revolution to form a completed receptacle, and means for automatically removing the receptacle from said forming means and from said gripping means.
3. In a machine for forming receptacles, the combination with a forming means, of grippers co-acting therewith to cause automatic folding of a portion of a receptacle blank to form a receptacle, and means for automatically shifting the position of the receptacle while in process of formation.
4. In a machine for forming receptacles from blanks, the combination with a pivotably mounted forming means, of grippers adapted to grip a blank, and turn a portion of the same through a part of a revolution to form a receptacle, and means for automatically creasing the folded portion of the receptacle.
5. In a machine for forming receptacles from blanks, the combination with a forming means, of grippers co-acting therewith adapted to grip a blank and turn a portion thereof through a part of a revolution to form a receptacle, means for automatically creasing the folded portion of the receptacle, and a mechanism for automatically shifting the receptacle during the process of formation.
6. In a receptacle forming machine, the combination with a forming means, of a timing member forming a part thereof, gripping means adapted to grip a receptacle blank and fold a portion of the same to form a receptacle, a shaft operated from the machine, and cam means thereon for actuating the gripping means.
7. In a receptacle forming machine the combination with a driving means, of a forming device driving shaft, a forming device operated thereby, a manually adjustable timing mechanism forming a part of the forming device, a feeding device driving shaft, and gear mechanisms connecting both of the above shafts with the driving means.
8. In a receptacle forming machine the combination with a driving means, of a forming device driving shaft, a forming device operated thereby, a manually adjustable timing mechanism forming a part thereof, and a gear train connecting said shaft with the driving means adapted to cause said shaft and the forming device to be intermittently operated.
9. In an automatic machine for forming conical receptacles, the combination of an intermittently operated forming means, said
- means including a manually adjustable timing member, and gripping means adapted to grip the prepared blank and turn a portion of the same through a part of a revolution to form the completed dish. 70
10. In an automatic machine for forming conical receptacles, the combination of an intermittently operated forming means, said means including a manually adjustable timing member, gripping means adapted to grip the prepared blank and turn a portion of the same through a part of a revolution to form the completed dish, and a forming means cooperating with said gripping means. 80
11. In an automatic machine for forming conical receptacles, the combination of an intermittently operated forming means, said means including a manually adjustable timing member, gripping means adapted to grip the prepared blank and turn a portion of the same through a part of a revolution to form the completed dish, a forming means cooperating with said gripping means, and means for automatically shifting said forming means at predetermined times to permit of the free turning of the gripping means. 85
12. In an automatic machine for forming conical receptacles, the combination of an intermittently operated forming means, said means including a manually adjustable timing member, gripping means adapted to grip the prepared blank and turn a portion of the same through a part of a revolution to form the completed dish, and cam members for operating the gripping means. 90
13. In an automatic machine for forming conical receptacles, the combination of an intermittently operated forming means, said means including a manually adjustable timing member, gripping means adapted to grip the prepared blank and turn a portion of the same through a part of a revolution to form the completed dish, and cam members for operating the gripping means. 105
14. In an automatic machine for forming conical receptacles, the combination of an intermittently operated forming means, said means including a manually adjustable timing member, gripping means adapted to grip the prepared blank and turn a portion of the same through a part of a revolution to form the completed dish, cam members for operating the gripping means and the forming means; and a separate driven cam shaft on which said cam members are mounted. 110
15. In an automatic machine for forming conical receptacles, the combination of an intermittently operated forming means, said means including a manually adjustable timing member, gripping means adapted to 120
- 130

- grip the prepared blank and turn a portion of the same through a part of a revolution to form the completed dish, cam members for operating the gripping means and the forming means, a separately driven cam shaft on which said cam members are mounted, and means for continuously operating said cam shaft.
16. In an automatic receptacle forming machine, the combination of a feed table, forming means cooperating therewith, blank feeding means adjacent the feed table, pivoted positioning means projecting through the feed table to insure proper relation between a prepared blank and the forming means, cam members for operating the forming means, and cam means for actuating the pivoted positioning means at a predetermined time to shift a blank being formed into a receptacle.
17. In an automatic receptacle forming machine, the combination of a feed table, forming means cooperating therewith, blank feeding means adjacent the feed table, positioning means on the feed table to insure proper relation between a prepared blank and the forming means, pivoted means co-acting with the forming means to crease the blank, and cam members for operating the forming means, the pivoted means, and the positioning means, said cam members being positioned on the driving shaft for the feeding means.
18. In a receptacle forming machine, the combination of a feeding means, a forming means, a table with which the forming means cooperate, positioning means on the table, means for actuating the positioning means at a predetermined time to push a partially formed receptacle a short distance off of the forming means, and ejecting means for removing a completed receptacle.
19. In a receptacle forming machine, the combination of a feeding means, a forming means, a table with which the forming means cooperate to crease a portion of a blank, positioning means on the table, pivoted means co-acting with the forming means to crease another portion of the blank, and ejecting means for removing a completed receptacle, said positioning and ejecting means being cam operated.
20. In a machine for forming receptacles, the combination of a forming means, blank gripping means coacting therewith, means for operating the grippers a plurality of times in the formation of each receptacle, means for shifting the position of the receptacle while in process of formation, and ejecting means for the completed receptacle.
21. In a receptacle forming machine the combination with a forming device, means for operating the same intermittently, and a manually adjustable timing mechanism forming a part of said forming device.
22. In a receptacle forming machine the combination with an intermittently operated forming mechanism, of a manually adjustable timing mechanism forming a part thereof.
23. In a receptacle forming machine the combination with a forming mechanism, of a table with which the forming mechanism cooperates to crease a portion of the blank, and a timing mechanism forming a part of the forming mechanism.
24. In an automatic machine for forming a conical dish, the combination with a forming means, gripping means forming a part thereof adapted to grip a blank, and cam members for operating the gripping means.
25. An automatic dish forming machine comprising mechanisms adapted to automatically grip a blank, and means for turning the gripping mechanism to fold a portion of the gripped blank to form a completed conical dish.
26. In an automatic dish forming machine the combination with a blank feeding means, of a forming means adapted to fold a blank into a conical dish, and a table with which the forming means co-acts to crease a folded portion of the dish.
27. In an automatic dish forming machine the combination with a blank feeding means, of a forming means adapted to fold a blank into a conical dish, a table with which the forming means co-acts to crease a folded portion of the dish, and a pivoted means co-acting with the forming means to crease another portion of the dish.
28. In a machine for forming receptacles, the combination with a means for forming a receptacle, of pusher bars for automatically shifting the position of the receptacle on said forming means while in process of formation.

In testimony whereof I have hereunto subscribed my name in the presence of two subscribing witnesses.

CESARE BARBIERI.
